CLAIM

The ornamental design for a heater as shown and described.

DESCRIPTION

FIG. 1 is a top perspective view of a heater showing the new design;

FIG. 2 is a right side elevational view of the embodiment of FIG. 1;

FIG. 3 is a front elevational view of the embodiment of FIG. 1;

FIG. 4 is a left side elevational view of the embodiment of FIG. 1;

FIG. 5 is a rear elevational view of the embodiment of FIG. 1;

FIG. 6 is top plan view of the embodiment of FIG. 1;

FIG. 7 is a bottom plan view of the embodiment of FIG. 1;

FIG. 8 is a top perspective view of an alternate embodiment of a heater showing the new design;

FIG. 9 is a right side elevational view of the embodiment of FIG. 8;

FIG. 10 is a front elevational view of the embodiment of FIG. 8;

FIG. 11 is a left side elevational view of the embodiment of FIG. 8;

FIG. 12 is a rear elevational view of the embodiment of FIG. 8;

FIG. 13 is top plan view of the embodiment of FIG. 8; and, FIG. 14 is a bottom plan view of the embodiment of FIG. 8. The broken lines shown in the drawings are included for the purpose of illustrating portions of the heater that form no part of the claimed design.
